GUIDING AND TRANSFER DEVICE

William T. Mohan, Pittsburgh, Pa.

Application July 3, 1940, Serial No. 343,885

4 Claims. (Cl. 80—51)

This invention relates to guiding and transfer devices, and more particularly to one which is adapted for guiding a bar or pipe to given location and subsequently transferring the same to a skidway or conveyer.

In the manufacture of seamless pipes and tubes, by way of example, it is customary to advance a solid or hollow workpiece between a plurality of metal-working rolls and an immediately disposed mandrel. It is extremely important that there be assured the proper entry and egress of the workpiece into and out of the pass defined by the metal-working rolls; otherwise serious complications result. The workpiece, which is advanced helically, acquires a vibratory motion, or "whisps" to such an extent as to have its quality impaired.

According to conventional practice, a given seamless pipe or tube mill may be so set up as to produce workpieces of differing outside diameters. That is to say, the metal-working instrumentalities of a mill may be so changed or adjusted as to afford the production of tubular workpieces of outside diameters which extend over a substantial range.

Accordingly, after there has been produced an order for tubular workpieces of a given outside diameter, the mill may be so changed or adjusted as to produce an order of tubular workpieces having a different outside diameter. In most cases it is also necessary to change the guide devices which are disposed coaxially of the line of pass and on the outlet bed of the mill. These guide devices substantially encircle the mandrel bar which supports the mandrel and also the tubular workpiece as it is advanced helically onto the mandrel bar. These guide devices control whipping to practical proportions and conventionally take the form of a series of aligned pairs of semicylindrical segments divided on the horizontal, the lower segment being stationary and the upper being susceptible of upward swinging movement to permit a transfer device to engage the bottom of the tubular workpiece after the mandrel bar has been withdrawn and to transfer the same onto a skidway or other conveying device. These conventional guiding devices, while somewhat practical in operation, are inflexible in function as they can only suitably control whipping of tubular workpieces whose outside diameters are within a relatively narrow range as compared with the operating range of the remainder of the mill. Therefore, these conventional guide devices must be frequently changed; and this requires several hours' time, which occasions a high cost of production, and often an entire loss of profit, particularly if a small order is being produced.

It is one of the objects of the present invention to provide a novel guiding and transfer device of a type which is applicable to seamless

pipe and tube mills; the said device being operable not only to function as a guiding instrumentality through a wide range of variations in outside diameter of the tubular workpiece, but one which, at the same time, functions to transfer the tubular workpiece from the outlet bed of the mill onto a suitable skidway or other conveying device.

Another object is the provision of a combined device of the class described which may be operated in but a few moments' time to cover a substantial range of sizes, and also to transfer in a similar period of time the tubular workpiece from the outlet bed of the mill.

Still another object is the provision of a combined device having the foregoing advantages and one which is, at the same time, relatively easy and inexpensive to manufacture, install, operate, and maintain.

The invention, then, comprises the features hereinafter fully described and as particularly pointed out in the claims, the following description and the annexed drawings setting forth in detail a certain illustrative embodiment of the invention, this being indicative of but one of a number of ways in which the principles of the invention may be employed.

In said drawings:

Figure 1 is a plan of the apparatus of the invention as used on the piercing pass of a seamless pipe or tube mill;

Figure 2 is a rear end elevation of the apparatus of Figure 1; and

Figure 3 is an enlarged view on the line III—III of Figure 1.

Referring more particularly to the drawings, the letter A designates a pair of suitably actuated metal-working rolls such as are commonly used in the manufacture of seamless pipes and tubes and which, in the present instance, are shown as being of the well known "Stiefel" or "cone" type. Intermediate the metal-working rolls A there is disposed a mandrel, designated at B, which interiorly supports the workpiece being processed and determines the inside diameter thereof. In the present instance this mandrel B is shown as a piercing plug which is used to transpose a solid billet into a tubular article or workpiece. Whether the mandrel B takes the form of a piercing plug, as shown in the drawings, or is of one of the other types well understood in the art as being susceptible of use on workpieces which have previously been pierced, it is in any event supported by a mandrel bar C which extends along the outlet bed of the mill and is attached to a reciprocable carriage (not shown). This reciprocable carriage (not shown) holds the mandrel B against the thrust of the workpiece and permits the latter to move completely onto the mandrel bar C and into the out-

let guides of the mill which, as previously stated, conventionally take the form of a series of aligned pairs of semicylindrical segments which are divided on the horizontal. After the workpiece is completely moved onto the mandrel bar C and into the guide devices, the mandrel B is removed from the advance or forward end of the mandrel bar and the latter is retracted and moved from within the workpiece by the rearward movement of the carriage.

According to the teachings of the present invention, there is disposed along the outlet bed of the mill suitable pedestals 2 which carry a pair of parallel longitudinally extending rotatable shafts 3 which occupy a common horizontal plane with and are spaced equidistant from the line of pass of the mill which is designated at X.

At suitable distances, and in opposed relationship, along the rotatable shafts 3 there is secured to each shaft a series of rotatable heads or turrets 4 to the periphery of which there is detachably secured, as by bolts and nuts 7 and 8 respectively, a series of semicylindrical segments 10, the cylindrical axes of which are parallel to the line of pass of the mill and, accordingly, the axes of the rotatable shafts 3.

It is to be especially noted that the semicylindrical segments 10 are so arranged that the ends thereof are not equidistant from the rotatable shaft 3 carrying the rotatable head 4 to which they are detachably secured. That is to say, when considered in conjunction with the arrows of rotation shown in Figure 3, the semicylindrical segments 10 carried by the rotatable head 4 on the right-hand side of said figure are so mounted that their forwardly moving ends are elevated, as shown at 10^a, with respect to the opposite ends 10^b thereof; while it is otherwise with respect to the semicylindrical segments 10 carried by the oppositely disposed rotatable head 4. Thus, it will be seen that when the semicylindrical segments 10 are moved into cooperative relationship in such manner as to be concentric about the line of pass X of the mill, the line of division between said segments, instead of occupying a horizontal plane in the manner of the semicylindrical segments of the prior art, occupies the position designated by the arrow in Figure 3.

Assuming a tubular workpiece 11 to be disposed in the guides formed by the aligned series of semicylindrical segments 10 of the present invention, the rotation of the rotatable shafts 3 in the direction of the arrows of Figure 3 will result in the supporting of the workpiece 11 by the semicylindrical segments 10 carried by the rotatable head on the left-hand side of said figure. The tubular workpiece 11 is so carried until the aligned semicylindrical segments 10 supporting the same occupy the position designated at Y, at which time it will be permitted to roll therefrom by gravity onto a suitable adjacently disposed skidway or other suitable conveyor 12. At this time, the shafts 3 are rotated, either by continuing in the same direction or by reversal, until the semicylindrical segments, designated at Y, occupy their previous position. This manner of operation is continued so long as tubular workpieces of the same diameter are being produced.

When a change is made in the outside diameters of the tubular workpieces being produced by the mill, the shafts 3 are suitably rotated until the properly sized semicylindrical segments 10 are aligned with the line of pass X of the mill,

and these particular semicylindrical segments 10 function in the manner recited hereinbefore.

In order to rotate the rotatable shafts 3 both for the purpose of aligning the semicylindrical segments 10 of the proper size, and also for transferring the tubular workpiece 11 onto the skidway 12, the pedestal 2 carries below the rotatable shaft 3 a pair of parallel rotatable shafts 15 whose axes occupy a common plane. The shafts 15 are adapted for joint rotation, as by means of the intermeshed gears 17, one of which is keyed to each of the said shafts. Each of the rotatable shafts 3 has secured thereto a gear 18, which meshes with one of the gears 11 carried by the shafts 15. One of the shafts 15 also carries for conjoint rotation therewith a chain gear 21 which meshes with a silent chain 23 which is, in turn, connected to a chain gear 24 which is secured to the driven shaft 25 of a speed reducer 26, the latter being actuated in any suitable manner by an adjacent motor 28.

Suitable electric controls, including limit switches and the like, are provided for enabling the movement of the rotatable heads or turrets 4 in the manner previously described; but as such form no part of the present invention and are, accordingly, not shown.

While I have shown and described one specific embodiment of the present invention, it will be seen that I do not wish to be limited exactly thereto, since various modifications may be made without departing from the scope of the invention, as defined by the following claims.

I claim:

- 35 1. A guiding and transfer device for tube mills comprising, in combination, a series of opposed rotatable heads having their axes of rotation occupying substantially a common horizontal plane, a series of segments carried by each of said rotatable heads, each opposed pair of segments being so constructed as when in opposed relationship to substantially define a circle and when so disposed to be divided on a line offset with respect to the horizontal.
- 40 2. A guiding and transfer device for tube mills comprising, in combination, a series of opposed rotatable heads having their axes of rotation occupying substantially a common horizontal plane, a series of segments of different sizes carried by each of said rotatable heads, each opposed pair of segments being so constructed as when in opposed relationship to substantially define a circle and when so disposed to be divided on a line offset with respect to the horizontal.
- 45 3. A guiding and transfer device for tube mills comprising, in combination, a series of opposed rotatable heads having their axes of rotation occupying substantially a common horizontal plane, a series of detachable segments carried by each of said rotatable heads, each opposed pair of segments being so constructed as when in opposed relationship to substantially define a circle and when so disposed to be divided on a line offset with respect to the horizontal.
- 50 4. A guiding and transfer device for tube mills comprising, in combination, a series of opposed rotatable heads having their axes of rotation occupying substantially a common horizontal plane, a series of detachable segments of different sizes carried by each of said rotatable heads, each opposed pair of segments being so constructed as when in opposed relationship to substantially define a circle and when so disposed to be divided on a line offset with respect to the horizontal.
- 55 5. A guiding and transfer device for tube mills comprising, in combination, a series of opposed rotatable heads having their axes of rotation occupying substantially a common horizontal plane, a series of detachable segments carried by each of said rotatable heads, each opposed pair of segments being so constructed as when in opposed relationship to substantially define a circle and when so disposed to be divided on a line offset with respect to the horizontal.
- 60 6. A guiding and transfer device for tube mills comprising, in combination, a series of opposed rotatable heads having their axes of rotation occupying substantially a common horizontal plane, a series of detachable segments of different sizes carried by each of said rotatable heads, each opposed pair of segments being so constructed as when in opposed relationship to substantially define a circle and when so disposed to be divided on a line offset with respect to the horizontal.
- 65 7. A guiding and transfer device for tube mills comprising, in combination, a series of opposed rotatable heads having their axes of rotation occupying substantially a common horizontal plane, a series of detachable segments of different sizes carried by each of said rotatable heads, each opposed pair of segments being so constructed as when in opposed relationship to substantially define a circle and when so disposed to be divided on a line offset with respect to the horizontal.
- 70 8. A guiding and transfer device for tube mills comprising, in combination, a series of opposed rotatable heads having their axes of rotation occupying substantially a common horizontal plane, a series of detachable segments of different sizes carried by each of said rotatable heads, each opposed pair of segments being so constructed as when in opposed relationship to substantially define a circle and when so disposed to be divided on a line offset with respect to the horizontal.
